UNITED STATES PATENT OFFICE.

JEAN PIRA, OF OUGREE-LEZ-LIEGE, BELGIUM.

TIE PLATE FOR METAL RAILROAD TIES.

1,405,628.

Specification of Letters Patent. Patented Feb. 7, 1922.

Application filed November 29, 1921. Serial No. 518,584.

To all whom it may concern:

Be it known that I, JEAN PIRA, a subject of the King of Belgium, residing at 10 Quai Vercourt, Ougree-lez-Liege, Belgium, have 5 invented certain new and useful Improvements in Tie Plates for Metal Railroad Ties, (for which I have filed applications in Belgium on Oct. 22, 1921; Germany on April 17, 1919; France on Oct. 25, 1921; Great Britain on Nov. 7, 1921,) of which the following is a specification, reference being had 10 therein to the accompanying drawing.

This invention relates to railroad ties and the like, and consists in an improved supporting tie-plate intended for securing the rails to unperforated metal ties, the upper 15 face of the latter having lateral edges projecting on both sides.

According to the present invention, the 20 supporting tie-plate is provided on both sides with hooks engaging the projecting edges of the tie and is secured for example by a key driven between its hooks and the lateral projections before mentioned. In 25 this way the rail is secured in a simple manner but at the same time also with absolute effectiveness against lifting. It is then easy to provide known means for preventing sliding of the tie plate and of the rail in the longitudinal direction of the tie.

The annexed drawing represents one form 30 of construction in accordance with the invention:

Figure 1 is a side view of the attachment 35 of the rail to a tie, in section upon the line A—A—A of Figure 2.

Figure 2 is a plan of the same.

Figure 3 is a longitudinal section upon the line B—B of Figure 2.

40 Figure 4 is a top plan of the tie.

Figure 5 is a plan of the tie-plate.

45 Figures 6 and 7 are sections upon the lines C—C and D—D of Figure 5.

The supporting tie-plate *a* is provided at 50 its two edges lying in a direction parallel to the tie with hooks *b* and *c*, engaging around the edges *k* which project as above stated from the two sides of the tie. The securing 55 of the rail is effected as usual by means of the hook *d*, the washer-plate *g* resting against a rib *e*, and the bolt *h*. The hooks *b* and *c* are arranged at such a distance from one another that the tie-plate *a* can be laid or dropped vertically upon the tie *l* having 60 the lateral projections *k*. The vertical fixing of the tie-plate *a* is insured by a key *m*

engaged between the flange *b* of the tie-plate and the lower face of the flange *k* upon the tie *l*. Key *m* is slightly tapered in a vertical plane, as indicated in Fig. 3, so that 60 when driven into position it will have a wedging action between flange *b* and the lower face of flange *k*.

To prevent longitudinal sliding of the tie 65 plate *a* along the tie *l*, the latter is formed with a T-shaped depression obtained by stamping or in any other suitable manner.

Within the portion *i* of the depression, 70 perpendicular to the longitudinal axis of the tie, there is fitted a corresponding rib *j* upon the tie-plate *a*. The portion *n* of the hollow in the tie, situated in the longitudinal axis of the latter, serves to receive the head of the bolt *h* securing the rail *f* upon the tie-plate *a*. The projection *j* is obtained either 75 by stamping or by rolling during the manufacture or preparation of the tie-plate. An elongated rectangular hole *o* is provided in the tie plate to receive the bolt *h*, as in the ordinary practice.

It will readily be observed that the vertical fixing of the rail upon the tie, obtained 80 by means of the tie-plate described above, is very simple and that in combination with the currently employed or other known 85 means for preventing horizontal sliding of the rail upon the tie, it is adapted to afford perfectly safe methods of securing rails upon unperforated metal ties, for example such a method as that illustrated in the 90 annexed drawing, in which the number of accessories is reduced to the strict minimum.

Claims:

1. A tie-plate for metal railroad ties, comprising a base, means for securing the rails 95 thereto, parallel hooked flanges along edges of said base at right angles to the rail, said flanges engaging round projections at the upper longitudinal edges of the tie, and means for fixing said flanges to the tie.

2. In combination with a metal railroad tie, having lateral projections along the upper longitudinal edges, a tie-plate comprising a base adapted to seat upon said tie, hooked flanges along two edges of said base, 100 said flanges being parallel and spaced apart to pass clear of said projections, and means for securing said flanges to said projections.

3. In combination with an unperforated metal railroad tie having lateral undercut 105 projections along its upper longitudinal edges, a tie-plate comprising a base adapted

to seat upon said tie, parallel hooked flanges engaging around said projections, and a key adapted to be driven between one of said flanges and the corresponding projection.

5. 4. In combination with an unperforated metal railroad tie having lateral projections along its upper longitudinal edges, a tie-plate comprising a base, adapted to seat upon said tie, parallel flanges upon said base, said flanges adapted to hook around said projections, means for securing said flanges to said projections, a hook upon the upper face of said base, said hook engaging the bottom of the rail, and a bolt passing through said base, said bolt engaging the bottom of the base and having its head located in a depression on the upper face of the tie.
- 10 5. The combination with a railroad rail, 20 of a metal tie, said tie having lateral pro-

jections along its upper longitudinal edges and a T-shaped depression in its upper face, and of a tie-plate comprising a base adapted to seat upon said tie, a rib upon said base entering one portion of said T-shaped depression, parallel flanges engaging around said projections, means for securing said flanges to said projections, and of means for fastening the rail to said tie plate, said fastening means including a bolt passing through said base and having its head located in the other portion of the depression in said tie. 25 30

In testimony whereof I hereunto affix my signature.

JEAN PIRA.
